Primary Examiner — Patricia A Palasik*(74) Attorney, Agent, or Firm* — Muncy, Geissler, Olds & Lowe, P.C.(57) **CLAIM**

I claim the ornamental design for an oil injector, as shown and described.

DESCRIPTION

FIG. 1 is a top, front, right perspective view of an oil injector showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom, front, left perspective view.

The broken lines in the drawings illustrate portions of the oil injector which form no part of the claimed design.

The dot-dashed line in the figures defines the boundary of claimed design and forms no part of the claimed design.
